UNITED STATES PATENT OFFICE

2,632,893

MAN'S TIE

Joseph Melville, Long Beach, N. Y.

Application August 19, 1948, Serial No. 45,061

1 Claim. (Cl. 2—144)

1

This invention relates to men's ties.

It is an object of the present invention to provide a tie which has two fan ends of similar design or color patterns and which when tied will display either one of the designs depending which of the fan ends is on top or outermost and wherein the tie can be worn again with the other design being outermost when the tie is again connected to the neck of the wearer.

It is another object of the present invention to provide a simple method of forming a tie having two fan ends of similar design or shape.

It is another object of the present invention to provide a tie which has two fan portions with folds which may be expanded to the opposite sides whereby to give a more full display of the tie patterns or designs and to make full use of the material which goes into the tie, and wherein the lower ends of the portions have a serpentine curvature therein that extends throughout the lower ends of folds and facilitates the inward folding of the folds and the retention of the same when folded or extended and as well to improve the appearance of ties.

Other objects of the present invention are to provide a double pattern tie with side folds, which is of simple construction, inexpensive to manufacture, easy to tie and of pleasing appearance and may be effectively displayed.

For other objects and for a better understanding of the invention, reference may be had to the following detailed description taken in connection with the accompanying drawing, in which

Fig. 1 is a plan view of the end portions of the tie extended to display the different figures on the respective portions and wherein the side folds of each portion are extended laterally.

Fig. 2 is a perspective view of the tie bent in half but portraying different figures on the different end portions.

Fig. 3 is a perspective view of the tie having the figures shown in Fig. 2 connected about a collar but with the side folds folded in.

Fig. 4 is a transverse sectional view taken on line 4—4 of Fig. 2 and looking in the direction of the arrows thereof.

Referring now to the figures and particularly to Fig. 1, 10 represents one fan portion or section of a tie having one kind of figure or design 11 thereon and 12 represents a second fan portion or section having a different figure 13, but preferably of similar color pattern thereon. The different fan portions 10 and 12 are made up separately of different figured material and are joined on a bias as indicated at 14 to provide a

2

portion adapted to be extended about the neck. The different fan portions, while having different figures of one color, also have an opposite color background. It is conceivable that many different figures can be used with these different portions. The color contrasts of the figures and background are preferably the same on the two portions.

In order to add to the display of the figure and to render the tie more attractive when on display, each fan portion has side folds 15 and 16 formed of the same material and creased as indicated at 17 to provide for the folds. These side folds are folded inwardly at the inner fold when the tie is worn as shown in Fig. 3.

Referring now particularly to Figs. 2 and 3, a similar double end tie is shown having respectively different figures thereon than from that shown in Fig. 1. The different figures or designs for the tie shown in Figs. 2 and 3 are indicated at 18 and 19 on respective fan portions 21 and 22 having respectively folded side extensions 32 similar to the folded extensions 15 and 16 of the tie shown in Fig. 1. These side folds are, when the tie is worn, extended inwardly as shown in Fig. 3. The figure or design 19 may appear outermost as shown in Fig. 3 or the tie may be removed and retied wherein the figure or design 18 may appear outermost, the knot being as indicated at 24 and the connection between the fan portions being extended about and beneath a collar 25 of a shirt 26.

As shown at 28 in both ties, the end edges are cut to have a serpentine curvature. This curvature extends throughout the extent of the folds and facilitates the folding of the side extensions inwardly and outwardly. This cutting provides for a blunt rounded center edge portion 29 which will not readily enter or engage objects that may tend to dirty the tie end.

It will be apparent that any number of folds can be used on the side portions depending upon the width of the fan portion and the extent to which it is most feasible to position the side fold extensions. It is preferable that each side fold extension be extended a distance equal to at least one half the unfolded width of the fan portion. It will also be apparent that the folds may extend the full height of the fan portion. With the folds extended, substantially the entire material of the tie fan portion is displayed. It will also be apparent that there has been provided a simple method of forming a two-in-one tie with the two fan portions of similar shape but of different figure or design.

It should be further apparent that there has been provided a tie which is virtually two ties in one. Either one of the portions may be displayed depending upon the manner in which the tie is tied or knotted.

While various changes may be made in the detail construction, it shall be understood that such changes shall be within the spirit and scope of the present invention as defined by the appended claim.

I claim:

A tie construction having a fan portion with side fold extensions therein adapted to be extended to show the full extent of the material when the tie is being displayed, each of said side fold extensions having a plurality of laterally spaced creases spaced inwardly from each edge thereof and extending a substantial distance upwardly from the lower end of the fan portion, and the lower ends of said fan portion being cut 20 to serpentine shape particularly along the lower ends of the side fold extensions to facilitate the manipulation of the side fold extensions, said

lower edge including a blunt rounded tip formation at the center of the fan portion so that the tie end will not readily enter or engage objects and will be prevented thereby from becoming 5 dirtied.

JOSEPH MELVILLE.
